Exner:

By - his Attorney H. J. England.

UNITED STATES PATENT OFFICE.

WILLIAM EXNER, OF HARPER'S FERRY, ASSIGNOR OF ONE-HALF TO
CHARLES H. WOLFES, OF MARTINSBURG, WEST VIRGINIA.

CUT-OFF AND SPOUT.

SPECIFICATION forming part of Letters Patent No. 362,917, dated May 10, 1887.

Application filed October 20, 1886. Serial No. 216,710. (No model.)

To all whom it may concern:

Be it known that I, WILLIAM EXNER, a citizen of the United States, residing at Harper's Ferry, in the county of Jefferson and State of West Virginia, have invented certain new and useful Improvements in Cut-Offs and Spouts; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to certain new and useful improvements in water-spouts; and it consists in a spout-leader with two or more diverging spouts arranged near the delivery, a cut-off valve working within the main spout and adapted to cut off the discharge of water from either diverging pipes at will, the object of my invention being to change the direction of discharge-water from the roof of a building (after it has become clear) from waste or drain to the cistern for house use. I attain these objects by means of the peculiar construction and arrangement of the various parts of my device, which will be more fully pointed out and described in the specification and claim, reference being had to the drawings accompanying this application and forming part of the same, in which—

Figure 1 is a vertical sectional view of my invention, and Fig. 2 is a detail perspective view of valve.

Similar letters refer to like parts throughout the drawings.

Referring to the drawings, A represents a main water-spout leading from the eaves-trough or guttering to a point near the ground.

B and C represent diverging pipes that open into and are connected to the main pipe A at its lower extremity on the sides of the same, as the extreme lower end of main pipe A is inclosed by metal in V shape, with a central slotted perforation, a, adapted to receive

and loosely hold the handle of valve D, which is made oval in shape around its edges and flat on its upper and lower face. From the center of said valve projects a stem or handle, D', a portion of which from the face of valve D outward is formed flat or angular, the purpose of which is to prevent the stem and valve D from turning when the stem is drawn down and the valve rests in place, the valve D being turned by pushing the stem inward until the valve is raised from its seat, and the round part of the stem moves freely in the slot a, when the valve can be turned round from pipe B to pipe C, changing the course of the water from spout A to the cistern or ground, as desired.

About two-thirds of valve D is provided with an extension, E, that loosely fits around the inside of spout A and between it and an inner casing, A', which is secured by its upper edge to the spout A, with a beveled or inclined surface to permit the descending water to pass freely into the inner casing, A'. The inner edges of extension E are curved, c, near the valve D to conform to the opening in pipes B and C, so that when the valve D and extension E shut off the water from pipe C a free open passage is left through pipe B, as shown in Fig. 1, and reversing the valve shuts B and opens pipe C.

I claim—

In a cut-off and spout, the main pipe A, having inner casing, A', the curved discharge-pipes B and C, having a central slot, a, in combination with the inclined valve D, formed to fit the inclined inner face of the discharge-pipes and provided with the curved extension E, and the valve-stem D', having an angular upper shoulder, b, all arranged and operated substantially as shown and described.

In testimony whereof I affix my signature in presence of two witnesses.

WILLIAM EXNER.
